CLAIM

The ornamental design for a cradle for an intraoral scanner, as shown and described.

DESCRIPTION

1. Cradle for intraoral scanner

1.1 : Front

1.2 : Back

1.3 :Top

1.4 :Bottom

1.5 : Right

1.6 : Left

1.7 : Perspective view 1

1.8 : Perspective view 2

1.9 : Perspective view 3

1.10 : Perspective view with the lid removed 1

1.11 : Perspective view with the lid removed 2

1.12 : Perspective view 1 with the hanger rotated 30 degrees

The article is a cradle for placing an intraoral scanner which is a device for scanning a three-dimensional shape of an interior of an oral cavity mainly in dental treatment; the hanger of the article can be rotated 30 degrees to the left and right relative to the base of the article when viewed from the right side; the parts shown in dotted lines do not form part of the claimed design.
